UNITED STATES PATENT OFFICE.

ALBERT MORLEY, OF THREE OAKS, MICHIGAN.

HEADLIGHT FOR AUTOMOBILES.

1,285,314.

Specification of Letters Patent. Patented Nov. 19, 1918.

Application filed November 25, 1916. Serial No. 133,295.

To all whom it may concern:

Be it known that I, ALBERT MORLEY, a citizen of the United States, residing at Three Oaks, in the county of Berrien and State of Michigan, have invented a certain new and useful Improvement in Headlights for Automobiles, of which the following is a specification.

My invention relates to headlights for 10 automobiles and has for its object to provide convenient means whereby a single headlight may be utilized to give alternately as required a strong forward beam of light and a strong lateral beam to illuminate the side of the road when, for any reason, it is desirable to discontinue the use of the forward reflecting light. Of course both of the lights could be simultaneously operated.

20 This general object is accomplished by incorporating in one and the same lamp or reflector system two or more reflectors and two or more lamps, the focal light of the reflectors being at an angle to each other.

25 I have shown my invention somewhat diagrammatically, although the structure here illustrated is in fact taken from a working lamp. I have shown the lamp arranged with two reflectors only, though there might be more in the same reflector system. I wish my drawings to be taken as in a sense diagrammatic.

30 So far as the invention is illustrated that illustration is found in the accompanying drawings, wherein

Figure 1 is a diagrammatic view of two lamps supposed to be placed in position on opposite sides of the automobile;

35 Fig. 2 is an enlarged front view of one of the lamps;

Fig. 3 is an enlarged rear view of one of the lamps;

Fig. 4 is a cross section on line 4—4 of Fig. 2;

40 Fig. 5 is a similar section of a modification of Fig. 2.

Like parts are indicated by similar letters in all the figures.

45 A is a reflector adapted to direct the light forwardly.

B is a reflector adapted to throw the light to one side. The reflector A is provided with a centrally disposed lamp C with a suitable base C¹, and inleading wire C².

D is a lamp properly disposed in the reflector B and provided with a base D¹ and inleading wires D².

The reflector B is in part placed in the rear of the reflector A and hence to avoid projecting the associate parts too far toward the rear, it is desirable to place the lamp D in an inclined position as indicated in Fig. 4, though of course it can be placed as indicated in Fig. 5. In any event this lamp is in the rear of the main reflector A and in rear of the lamp C of that reflector.

I am not showing in any detailed manner the arrangement of the several parts, nor do I wish to be limited to the size, form, proportion and arrangement of the parts illustrated, as of course great variations in these could be made. It is my purpose to stamp or draw a single reflector into a suitable shape or form and this shape of course may greatly vary from that shown.

50 The use and operation of my invention are as follows:—

Lamps of the character suggested may be mounted each on the forward end and at one side of the automobile. The main reflector and lamp are of such size, shape and character as to give a beam of light of relatively great power, and this beam of light is directed forwardly along the road. Experience shows that a strong beam of light is undesirable where automobiles are approaching each other from outside directions.

If, however, the strong light commonly used be cut off at the moment when the automobile is about to pass another, a new danger occurs particularly where traveling on a narrow country road. The driver wishes to drive as nearly as possible on the edge of the road, or as far from the approaching car as possible, and for this purpose the side of the road ought to be illuminated.

55 By the arrangement shown, this result can be accomplished. The operator can of course, if he desires it, have both lamps, or if there be more than two reflectors and lamps in a single construction, then all of his lamps energize at the same time. In any event when he approaches another car he will switch out the main or forwardly directed lamp or lamps so as to diminish the brilliancy of his headlights. The secondary lamp with its reflector is then energized, if not already in action, and its rear light 60

is directed in accordance with its predetermined position. If such secondary reflector is toward the inside of the car and at one side of the main reflector and slightly above it, the effect will be of course to illuminate the edge of the road at the danger line.

The focal lines or axes of the two or more reflectors are for this reason inclined to each other as indicated.

10. In order that the main reflector may not be materially illuminated after its light has been cut off, the secondary reflector is placed back of the main reflector, and its light back of the main reflector, so that no considerable, 15 or at least a very much reduced reflection proceeds from the main reflector. For the purpose of putting the headlight in the smallest possible compass, it is desirable that the base and associate parts of the lamp of 20 the secondary reflector should be placed substantially at right angles and in close proximity to the corresponding parts of the main reflector lamp. Thus the entire headlight can be placed in and supported by the ordinary casings.

I claim:

1. A headlight reflector with a secondary reflector situated in its margin and lying entirely within its periphery, an independent 30 lighting means located within the secondary reflector and adapted to operate alone and independently of the main operating means, said lighting means situated in rear of the lighting means of the main reflector, the 35 axes of the main and secondary reflectors being at an angle one to another, the secondary reflector so situated that when its lighting means is operating alone there will be

no reflection of that lighting means from the main reflector.

2. A headlight for vehicles and the like comprising a main parabolic reflector, a source of light at the focus thereof, an auxiliary parabolic reflector integral with the main reflector having its reflecting surface partially at one side of and partially at the rear of the main reflector, the light source at the focus of the auxiliary reflector, the axes of the two reflectors being inclined one to another, the reflectors being so positioned that light from the source in the auxiliary reflector cannot be reflected from the main reflector and light from the main source cannot be reflected directly from the auxiliary reflector.

3. A headlight containing a main reflector and an auxiliary reflector inset within its side and integral with it, an independent source of light in each reflector, the two reflectors being so positioned that the auxiliary source of light cannot be reflected from the main reflector.

4. In a headlight a main reflector a source of light therefor an auxiliary reflector inset within the side of the main reflector, said auxiliary reflector so positioned that light from the main source of light cannot be reflected from it.

In testimony whereof I affix my signature, in the presence of two witnesses, this 17th day of November, 1916.

ALBERT MORLEY.
